UNITED STATES PATENT OFFICE.

FREDERICK HERBERT WILLIAM HIGGINS, OF LONDON, ENGLAND, ASSIGNOR
OF ONE-HALF TO RANDALL DAVIES, OF LONDON, ENGLAND.

TYPE-PRINTING TELEGRAPH.

SPECIFICATION forming part of Letters Patent No. 745,279, dated November 24, 1903.

Application filed August 11, 1902. Serial No. 119,267. (No model.)

To all whom it may concern:

Be it known that I, FREDERICK HERBERT WILLIAM HIGGINS, a subject of the King of Great Britain and Ireland, residing at 17 and 5 18 Cornhill, in the city of London, England, have invented certain new and useful Improvements in Type - Printing Telegraphs, (for which I have made application for Letters Patent in Great Britain, No. 14,430, dated 10 June 25, 1902,) of which the following is a specification.

My invention relates more especially to telegraphic instruments in which a type-printing receiving instrument has its type-wheel 15 driven by means of an escapement-wheel propelled by an electrically-reciprocated lever having propelm-pallets. In such instruments as hitherto constructed the limit of speed possible does not exceed about sixty 20 revolutions of the type-wheel per minute.

My invention has for its object to obtain much higher rates of revolution of the type-wheel, so that a greater number of words may be transmitted in a given time.

25 My invention consists in arranging the pallets with respect to the escapement-wheel in such a manner that the pallets move through a considerable arc, and thereby attain considerable velocity before striking the teeth

30 of the escapement-wheel, the propelm-lever abutting against suitable stops directly after contact, with the result that the impact between the pallet and escapement-wheel is of the nature of a sudden blow the energy of 35 which is sufficient to cause the escapement-wheel and other parts carried on the same axis to complete their arc of movement, as hereinafter explained, by their acquired momentum, rebound being prevented by spring- 40 pressed pawl engaging with a ratchet-wheel having double as many teeth as the escapement-wheel and on the same axis.

Referring to the accompanying drawings, Figures 1 and 2 are end and side elevations, 45 respectively, of the escapement-wheel, propelm-lever, and ratchet-wheel. Fig. 2 also shows the electromagnets under the action of which the propelm-lever reciprocates.

According to one modification of my invention I construct the escapement-wheel a on the type-wheel axis b with teeth c of coarse

pitch, the leading faces $c' c^2$ of each tooth being practically radial, while the back or driven faces $d' d^2$ of each tooth are slightly curved. The propelm-lever e is pivoted about an 55 axis f at one end and at the other end branches into two arms $e' e^2$, partially embracing the escapement-wheel. These arms are provided with pallet-faces f' and f^2 , respectively, which alternately come into contact with a tooth of the escapement-wheel as the propelm-lever reciprocates, and also with faces $h' h^2$, which limit the successive arcs described by the escapement-wheel at high speeds. I also provide on the type-wheel 60 axis b a ratchet-wheel i , having, preferably, twice as many teeth as the escapement-wheel, and a pawl i' , controlled by a spring i^2 , which is so arranged as to lock with one of the ratchet-teeth and prevent a reversal of the 65 direction of rotation of the type-wheel shaft just when the escapement-wheel has completed its free arc of movement under its own momentum in a manner to be explained hereinafter. 70

I provide two stops $k' k^2$, one on each side of the propelm-lever, to limit its travel in each direction, and preferably provide these stops with buffers $l' l^2$, held out by springs, 75 such as $m' m^2$.

The propelm-lever is caused to reciprocate by electromagnets in accordance with impulses received from the transmitting instrument or by an electromagnet and a spring. The resulting direction of rotation is indicated 80 by an arrow in Fig. 2.

According to the arrangement illustrated in Fig. 2 an arm n is fixed to the shaft f , on which the lever e is mounted, and carries the armatures $o' o^2$ of the electromagnets $r' r^2$, respectively. By suitably energizing the electromagnets the arm n , and consequently the lever e , is caused to reciprocate.

To explain the action of the mechanism, it is necessary to point out that, supposing the 95 escapement - wheel to have fourteen teeth, then, although fourteen complete reciprocations of the propelm-lever are necessary to rotate the escapement - wheel on its axis once at all speeds, nevertheless the action of the mechanism is somewhat different at high and low speeds, for, supposing first the pro-

pelment-lever to be operated very slowly, one of the propelm-pallets— f' , for instance—will abut against a face d' of a tooth of the escapement-wheel and push the wheel round through a certain arc until the propelm-lever's motion is stopped by the buffer l^2 provided. The motion of the lever will then be reversed and the other pallet-face, f^2 , will similarly act on a corresponding face of another tooth of the escapement-wheel, which will be driven round through a further arc. It will be seen from this description that at low speeds a pallet-face after abutting against a tooth of the escapement-wheel remains in contact with it until the further motion of the propelm-lever is stopped by the buffers. The escapement-wheel, therefore, at low speeds does not describe any free arc of movement out of contact with the propelm-pallets. If, however, the propelm-lever is rapidly reciprocated, the action is different, for, supposing the lever e at some stage of its motion to be in contact with the stop k' and about to move across to the other stop k^2 , the first part of its motion—that is to say, until the pallet-face f' has come into contact with a face d' of a tooth of the escapement-wheel—takes place at a continuously-increasing velocity, since the electro-magnets driving the lever e have at this stage only its inertia to overcome. By the time, therefore, that the pallet-face f' abuts against an escapement-wheel tooth the lever e has attained a considerable velocity. The pallet-face f' will remain in contact with the face d' of the escapement-wheel until the lever e completes the remaining small arc of its motion and is stopped by the buffer l^2 . At high rates of reciprocation this small arc is so quickly passed over by the lever e that its action with the escapement-wheel is of the nature of a blow, the escapement-wheel flying forward in the direction of the arrow after the motion of the lever e has ceased until the radial face c' comes into contact with the face h' on the lever e and further motion is prevented. Just at this moment the pawl i' locks with a tooth of the ratchet-wheel and prevents rebound. The mechanism is then in the position shown in Fig. 2. The return movement of the lever e operates in a similar manner on the face d^2 until the radial face c^2 of an escapement-tooth is stopped by the face h^2 on the lever e . It will be seen, then, that at high speeds the escapement-wheel describes a free arc of movement out of contact with the propelm-lever.

I find that with the disposition of propelm-pallets and escapement-teeth described and illustrated I am able to attain very high working speeds far in excess of any previously obtained and without the assistance of auxiliary motors, this increased speed being due to the free arc of movement described by the escapement-wheel, this free arc in the first place allowing the lever e more space in which to increase its velocity during its next recip-

rocation and in the second place insuring that the next tooth of the escapement-wheel is acted upon by the propelm-pallets at each reciprocation. With similar mechanisms constructed hitherto it is found that when very high speeds are attempted a propelm-pallet may enter the gap between two teeth of the escapement-wheel at consecutive reciprocations without causing the wheel to advance thus throwing the transmitting and receiving instruments out of synchronism.

It is obvious that such a mechanism may be used for other purposes than printing telegraphy.

Having now described my invention, what I claim as new, and desire to secure by Letters Patent, is—

1. In type-printing-telegraph receiving instruments, means for obtaining increased speed of rotation of the type-wheel shaft, comprising an escapement-wheel mounted on the type-wheel shaft, teeth thereon, a lever pivoted at one end operating said shaft, propelm-pallets at the other end of said lever, electrical means for causing said lever to reciprocate and said propelm-pallets being so disposed with regard to the escapement-wheel that they move through a considerable arc and thereby attain a considerable velocity before striking the teeth of the escapement-wheel with which they remain in contact for only a small part of the arc of movement of the escapement-wheel, the major portion of this arc being covered by the momentum acquired during contact with the propelm-pallets, all substantially as set forth.

2. In type-printing-telegraph receiving instruments, means for obtaining increased speed of rotation of the type-wheel shaft comprising an escapement-wheel mounted on the shaft to be driven, teeth on said wheel, a lever pivoted at one end operating said wheel, propelm-pallets at the other end of said lever, spring-buffer stops, and electrical means for causing said lever to reciprocate between said stops, and said propelm-pallets being so disposed with regard to the escapement-wheel that they move through a considerable arc and thereby attain a considerable velocity before striking the teeth of the escapement-wheel with which they remain in contact for only a small part of the arc of movement of the escapement-wheel, the major portion of this arc being covered by the momentum acquired during contact with the propelm-pallets, all substantially as set forth.

3. In type-printing-telegraph receiving instruments, means for obtaining increased speed of rotation of the type-wheel shaft, comprising an escapement-wheel mounted on the shaft to be driven, teeth on said wheel, a lever pivoted at one end operating said wheel, propelm-pallets at the other end of said lever, spring-buffer stops, and electrical means for causing said lever to reciprocate between said stops, and said propelm-pallets being so disposed with regard to the escapement-

wheel that they move through a considerable arc and thereby attain a considerable velocity before striking the teeth of the escapement-wheel with which they remain in contact for 5 only a small part of the arc of movement of the escapement-wheel, the major portion of this arc being covered by the momentum acquired during contact with the propelling-pallets and comprising also a ratchet-wheel 10 on the same axis as the escapement-wheel, teeth on said wheel, said teeth being disposed

in the reverse direction, and a spring-pressed pawl for locking with said ratchet-wheel at the end of each arc of movement, substantially as described.

15

In witness whereof I have hereunto set my hand in presence of two witnesses.

FREDERICK HERBERT WILLIAM HIGGINS.
